United States Patent Office

Des. 226,242
Patented Jan. 30, 1973

226,242

TOASTER

Reinhold M. Weiss, Chicago, Ill., assignor to The Gillette Company, Boston, Mass.

Filed June 25, 1971, Ser. No. 157,085

Term of patent 14 years

Int. Cl. D7—02

U.S. Cl. D81—10

Fig.1

Fig. 2

Fig. 3

Fig. 4

Fig. 5

FIG. 1 is a perspective view of a toaster showing my new design;

FIG. 2 is a front elevational view thereof;

FIG. 3 is a right side elevational view thereof;

FIG. 4 is a left side elevational view thereof; and

FIG. 5 is a top plan view thereof.

The undisclosed back is substantially a mirror image of the front.

I claim:

The ornamental design for a toaster, substantially as shown and described.
